UNITED STATES PATENT OFFICE

SAMUEL L. ADAMS AND DANIEL B. ADAMS, OF PICKENS, SOUTH CAROLINA

AUTOMATIC WATER CONVEYER OR CARRIER

Application filed December 6, 1930. Serial No. 500,656.

This invention relates to water carriers and lifters and particularly to means whereby a carrier may be filled at one point, shifted to a distance, emptied and then returned for re-
5 filling.

The primary object of the present invention is to provide an automatically and continuously actuated water transporting mechanism by which a pail may be dipped into a trough or pool of water, carried to a discharge position, tilted to discharge its contents and then returned, refilled, again discharged and so on continuously so long as the actuating mechanism is running.

15 A further object is to provide such a mechanism which is actuated by the power of a running stream of water.

A further object is to provide for this purpose two water wheels having relatively reversed buckets or blades and provide means acting automatically at intervals to direct the stream alternately against one wheel and then against the other, said wheels being operatively connected to a winding drum on which 25 is wound a cable connected to the bucket carrier.

Other objects have to do with the details of construction and arrangement of parts as will appear more fully hereinafter.

30 Our invention is illustrated in the accompanying drawings, wherein:—

Figure 1 is a diagrammatic view of a water conveying apparatus constructed in accordance with my invention, the upper portion of 35 the figure being in side elevation and the winding drum driving mechanism being in plan;

Figure 2 is a fragmentary cross section on the line 2—2 of Figure 1;

40 Figure 3 is a detailed view of the ring through which the cable passes;

Figure 4 is a vertical sectional view through the water wheels and through the drum;

Figure 5 is a side elevation of the drum;

45 Figure 6 is a cross section through the drum showing the way in which the cable is attached thereto;

Figure 7 is a top plan view of the water wheel chutes with the gate in a medial position but moving toward the left;

Figure 8 is a like view to Figure 7 but showing the gate in a position to deflect the water into the right hand chute;

Figure 9 is a sectional view through one of the chutes and a portion of one of the water 55 wheels on line 9—9 of Fig. 7;

Figure 10 is a like view to Figure 9 but showing the other water wheel and chute, and is a section on line 10—10 of Fig. 8.

Referring to these figures, 10 designates a 60 receptacle into which water is to be discharged and 11 upwardly extending posts on each side of the receptacle.

Between these posts a supporting wire 12 is mounted, this wire being inclined downward from a point above the receptacle 10 to a point above a pool of water designated generally 13, which water may be in an ordinary pool, a spring or a trough. For convenience, we have illustrated the pool of water as being contained within a trough 14. Extending between the posts 11 and above the wire 12

70 is a transverse rod 15. Operating upon the wire 12 is a carriage 16 having grooved wheels 17 engaging the wire and running 75 thereon and supported from this carriage is a link which swingingly engages the bail of a bucket 18 or other equivalent receptacle. At the bottom of this bucket, there is attached a cord 19 extending upward to an eye on a 80 pivoted arm 20. This arm is pivoted at 21

on the carriage and has an angularly extending arm 22. When the arm 20 is lowered, the arm 22 is raised and the bucket is swung downward. When the arm 22 is depressed, 85 the rear end of the bucket is raised. The bucket is provided with weights 18a at its mouth. The purpose of the mechanism now to be described is to intermittently haul the carriage rearward, that is, upward toward the discharge point and automatically tilt the bucket to discharge its contents into the receptacle 10 and then automatically allow the carriage to roll down the wire or track 12

90 with the bucket in the position shown in dotted lines, as in Figure 1 and allow the bucket to fill and then when the bucket is filled, retract the carriage to its discharge position. As the bucket moves toward its discharge position, the arm 22 will strike 95

100

Figure 7 is a top plan view of the water wheel chutes with the gate in a medial position but moving toward the left;

against the transverse rod 15. Thus as the carriage moves rearward, causing the rocking of the rod 20 and the lifting of the rear end of the bucket to discharge its contents into 5 the receptacle 10.

For the purpose of causing the movement of the carriage in opposite directions upon the wire or track 12, I provide a drum 23 mounted upon a shaft 24. Attached to this drum is 10 one end of a cable 25. When the bucket has been lowered to its filling position, all of the cable 25 has been drawn off of the drum 23 as shown in Figure 6 and then upon a further movement of the drum in the same direction, 15 the cable will be wound again upon the drum so as to draw the carriage upward to its discharge position.

Mounted upon the shaft 24 are two water wheels 26 and 27 having reverse blades or 20 buckets. Discharging water upon these water wheels respectively are the two chutes 28 and 29. These chutes are separated from each other by the intermediate longitudinally extending partition 30 and these chutes at their 25 inlet ends open into a single chute 31. Swingingly mounted upon the rear extremity of the partition 30 is a gate 32 adapted when fully swung in either direction to close one chute or the other of the chutes 28 and 29. Thus 30 when it is fully thrown to the right in Figure 1, all of the water coming through the chute 31 will be directed into the chute 28 and when the gate is swung fully to the left, all of the water passing downward through chute 31 35 will be discharged into the chute 29, as shown in Figure 8.

For the purpose of automatically operating this gate, we provide a transversely extending screw 33 mounted in suitable bearings 34, this 40 screw having upon it a traveling nut 35 carrying a pulley 36. This pulley may be swiveled to the traveling nut and is preferably grooved. Mounted upon the screw shaft 33 is a band wheel 37 and mounted upon the shaft 45 24 is a band wheel 38. Operatively connecting these band wheels for unitary motion is a band 39 illustrated as a cable. Any other suitable endless connection, however, may be used.

50 Passing through the pulley 36 and attached to the gate adjacent its free end is a rope 40. This rope extends through a pulley 41 anchored to any suitable object, as for instance to the tree stump designated 42. This rope 55 40 at its free end has attached thereto a ring 43. This ring is weighted at 44. The rope 25 passes through this ring 43 and has a stop 45 applied thereto beyond the ring 43.

Attached to the shaft 24 as by pinning or 60 otherwise is an arm 46, one extremity 47 of which overhangs the drum. Mounted upon this extremity of the arm is a brake band 48 extending down around the drum as illustrated in Figure 4 and at its free end provided with a bolt 49 extending upward

through the arm 47. These parts constitute a clutch.

In the operation of this device, assuming that the parts are in the position shown in Figure 1 and that the drum 23 is revolving in a clockwise direction and winding up the cable 25, then as the loaded bucket reaches its discharge position, the rod 15 as before stated will act to tilt the bucket and discharge its contents. Water is being discharged through 70 the chute 28 on the wheel 26 causing the rotation of the wheel in a direction to cause the winding up of the rope 25 upon the drum 23. As the bucket nears its discharge position and is overturned, the stop 45 will strike the ring 43 and a further movement of the cable or rope 25 will cause a strain to be exerted upon the rope 40 which will shift the gate from a position closing the chute 29 to a position closing the chute 28 and permitting 75 the water to pass through the chute 29 on to the chute 27. This will cause a reverse movement of the shaft 24. The weight of the carriage and of the empty bucket will cause the carriage to move downward from its discharge position to its filling position.

The drum 23 reverses its rotation and the stop 45, of course, moves away from the ring 43. The reverse rotation of the shaft 24 will, of course, cause the reverse rotation of the 80 screw so that the traveling nut 45 will travel to the other end of the screw carrying with it the pulley 36. When the rope 25 is run entirely off of the drum 23, the bucket will be filled and a further rotation of the drum 23 85 in this direction will cause a rewinding of the cable 25 upon the drum 23 but reversely to the manner in which it was previously wound. This will cause the pail to be again drawn from the water to its discharge position and 90 emptied and cause the stop 45 to again engage the ring 43, exerting a pull upon the cord 40, which, because the traveling nut 45 is now over toward the right in Figure 1 will cause a reverse movement of the gate 32 so that the 95 water will now pass through the chute 29 and reverse the action of the shaft 24, thus again reversing the action of the pulley and permitting the carriage to move again downward 100 by gravity to its filling position. The rope 105 25 will run entirely off the drum 23 and then a continued rotation of the drum in the same direction will again cause the winding up of the rope on the drum.

The drum is preferably loose upon the 110 shaft 24 but held in operative engagement with the shaft 24 by the brake band 48, this band being attached to the arm 46 which is fast on the drum. The band must be tight enough at all times to cause the rotation of the drum with the shaft 24 except when the stop 45 engages the ring 43. At this time, 115 the drum will slip within the band while the shaft is starting to reverse. When the shaft has fully reversed its motion, however, the 120

arm, the band and the drum will all rotate together.

We claim:—

1. The combination with a bucket supporting carrier and an inclined trackway on which the carrier moves, of means for automatically shifting the carrier alternately in opposite directions including two reversely bladed water wheels mounted on a common shaft, a winding drum operatively engaged by the shaft for rotation therewith, a cable on the winding drum and connected to the carrier, and means controlled by the movement of the cable on the winding drum whereby to direct water alternately over one or the other of said drums.

2. The combination with a bucket supporting carrier and an inclined trackway on which the carrier moves, of means for automatically shifting the carrier alternately in opposite directions including two reversely bladed water wheels mounted on a common shaft, a winding drum operatively engaged by the shaft for rotation therewith, a cable on the winding drum and connected to the carrier, and means controlled by the movement of the cable on the winding drum whereby to direct water alternately over one or the other of said drums, and including a gate shiftable to so direct the water, a screw extending transversely of the drums, a traveling nut mounted upon the screw and carrying a pulley, a rope connected to the gate and extending through said pulley, the rope passing through a second pulley and having a ring through which the cable passes, and a stop on said cable whereby when the cable is wound upon the drum to a predetermined extent, the stop will engage the ring to pull the rope and thereby shift the gate from one of its stream directing positions to the other.

3. The combination with a bucket supporting carrier, of an inclined trackway over which the carrier moves, of means for automatically shifting the carrier including two reversely bladed water wheels on a common shaft, a winding drum on the shaft, a cable on the winding drum connected to the carrier, said cable being of such length that when the carrier has reached one of its extremes of movement, the cable will be entirely unwound from the drum, and means to alternately reverse the motion of the winding drum comprising a screw extending parallel to the water wheels, a traveler mounted on the screw and having a pulley, means driven by the water wheels for rotating the screw, a gate adapted when shifted in one direction to direct water on to one of said water wheels and when shifted in the other direction to direct water on to the other of said water wheels, a cord attached to the free end of said gate passing through the pulley on the traveler, a second pulley through which said cord passes, the cord having a ring through which the first named cable passes, and the cable having a stop positioned so that when the cable is wound upon the drum to a degree sufficient to pull the carrier to the other extreme of its movement, the stop will engage the ring of the cord and pull said cord whereby to reverse the movement of the gate, the drum being loose upon the shaft, and a friction clutch normally engaging the drum with the shaft to permit the drum to move independent of the shaft at the time when the shaft is reversed.

ring through which the first named cable passes, and the cable having a stop positioned so that when the cable is wound upon the drum to a degree sufficient to pull the carrier to the other extreme of its movement, the stop will engage the ring of the cord and pull said cord whereby to reverse the movement of the gate.

4. The combination with a bucket supporting carrier, of an inclined trackway over which the carrier moves, of means for automatically shifting the carrier including two reversely bladed water wheels on a common shaft, a winding drum on the shaft, a cable on the winding drum connected to the carrier, said cable being of such length that when the carrier has reached one of its extremes of movement, the cable will be entirely unwound from the drum, and means to alternately reverse the motion of the winding drum comprising a screw extending parallel to the water wheels, a traveler mounted on the screw and having a pulley, means driven by the water wheels for rotating the screw, a gate adapted when shifted in one direction to direct water on to one of said water wheels and when shifted in the other direction to direct water on to the other of said water wheels, a cord attached to the free end of said gate passing through the pulley on the traveler, a second pulley through which said cord passes, the cord having a ring through which the first named cable passes, and the cable having a stop positioned so that when the cable is wound upon the drum to a degree sufficient to pull the carrier to the other extreme of its movement, the stop will engage the ring of the cord and pull said cord whereby to reverse the movement of the gate, the drum being loose upon the shaft, and a friction clutch normally engaging the drum with the shaft to permit the drum to move independent of the shaft at the time when the shaft is reversed.

5. The combination with a bucket supporting carrier, and an inclined trackway on which the carrier moves from one extreme position to the other, of means for automatically shifting the carrier including two reversely bladed water wheels, a chute for each water wheel, a chute emptying into the first named chutes, a gate hinged to the wall between the first named chutes and shiftable transversely thereof to direct the water on to one wheel or on to the other, the water wheels being mounted upon a common shaft, a drum shaft operatively connected to the shaft of the water wheels to be rotated thereby and carrying a drum thereon, a cable attached to said drum, and to the carrier, said cable when the carrier is in one of its extreme positions, being entirely payed off of the drum, a transversely extending screw disposed adjacent the path of movement of the free end of the gate and driven from said water

wheels, a traveler thereon having a pulley, a cord attached to the free end of the gate and passing through said pulley, a second pulley through which the cord passes, the cord having a ring through which said cable passes and a stop on the cable adapted when the carriage nears one of its terminal positions to engage said ring to thereby exert strain upon said cord and shift the gate from one of its positions to the other.

In testimony whereof we hereunto affix our signatures.
